UNITED STATES PATENT OFFICE.

EDWARD CARL NYQUIST, OF CHICAGO, ILLINOIS.

DESIGN FOR A STAND LAMP.

Application filed October 19, 1925. Serial No. 15,165. Term of patent 7 years.

To all whom it may concern:

Be it known that I, EDWARD CARL NYQUIST, a subject of the King of Sweden, residing at Chicago, in the county of Cook and State of Illinois, have invented a new, original, and ornamental Design for a Stand Lamp, of which the following is a specification, reference being had to the accompanying drawing, forming part thereof.

The figure is a perspective view of a stand lamp showing my new design.

I claim:

The ornamental design for a stand lamp, as shown.

EDWARD CARL NYQUIST.
